UNITED STATES PATENT OFFICE.

JOHN LOGAN, OF WALTHAM, MASSACHUSETTS.

METHOD OF AND APPARATUS FOR HARDENING STEEL RIBBON.

SPECIFICATION forming part of Letters Patent No. 297,610, dated April 29, 1884.

Application filed December 13, 1883. (No model.)

To all whom it may concern:

Be it known that I, JOHN LOGAN, of Waltham, county of Middlesex, State of Massachusetts, have invented an Improvement in 5 Methods of and Apparatus for Hardening Steel Ribbon, of which the following description, in connection with the accompanying drawings, is a specification, like letters on the drawings representing like parts.

10 My invention relates to the manufacture of steel springs, such as employed for the main-springs of watches and clock-work or for other purposes. In the process of manufacture of spring-steel as commonly practiced, the soft 15 steel, made into a ribbon or thin band of the proper shape, is drawn progressively through a furnace-muffle or a bath of highly-heated molten metal to give the steel ribbon a red heat, and upon issuing from the furnace or 20 bath the said metal is suddenly cooled, making it very hard and brittle, after which the ribbon, thus hardened, is tempered to give it the requisite elasticity. When a thin ribbon is thus drawn progressively through a furnace 25 or highly-heated bath, it quickly assumes the temperature of the material surrounding it, and is quickly affected by variations in temperature; and when it passes through a muffle or heated chamber not containing a liquid its 30 different parts are apt to be heated unequally, and the product is not uniform in character; and, furthermore, it requires great skill and care on the part of the operator to obtain a satisfactory result. In order to produce the 35 best spring-steel, the ribbon should be heated to a red heat gradually and uniformly throughout its entire length, and it is desirable to protect its surface from the action of air or other gases which tend to oxidize or chemically combine with it when at a high temperature, thus greatly diminishing the subsequent labor of polishing and finishing.

The present invention has for its object to insure the gradual and absolutely uniform 45 heating of the ribbon; and it consists, mainly, in providing an inclosing-case in which the said ribbon, when wound into a tight compact coil, is inclosed, the said case being heated, together with the inclosed ribbon, to the desired 50 temperature, and by its great mass or body causing the rise in temperature of the

inclosed ribbon to be gradual, and preventing any sudden changes in temperature, while the inclosed ribbon, being wound in a tight coil, occupies but small space, and is uniformly 55 affected in all parts. When the case, with the inclosed ribbon, has been heated to a proper temperature, the ribbon is unwound from the said case and drawn through the cooling-bath, or is otherwise suddenly cooled. The case for 60 containing the ribbon may be of various forms of construction, the one herein shown being made in two parts to receive the coil of ribbon between them, and being provided with a nose or passage, through which the ribbon is 65 drawn, the coil of ribbon turning on a suitable pivot or center in the case in unwinding.

Apparatus for hardening wire or ribbon has been made in which the said ribbon is drawn progressively through a muffle or chamber from which the air is excluded, as far as possible, by means of packing, and the ribbon is drawn directly from the said muffle into the cooling-bath, which is placed as near to the muffle as possible, so that the ribbon is but 70 slightly exposed to the air in its passage from the muffle to the bath. The ribbon has also been coiled in boxes, and hardened and tempered while held therein, so that the ribbon, when removed, retains the shape it had when 75 in the box, and this method cannot be followed when the finished ribbon is to have any other shape than that of a close-wound coil.

Figure 1 is a sectional view of an apparatus for hardening steel ribbon preparatory to tempering in accordance with this invention; Fig. 2, a side elevation of the ribbon-containing case and ribbon coiled thereon, the cover of the case being removed; and Fig. 3, a section of the said case with its cover on the 80 line *x*, Fig. 2.

The furnace *a*, muffle *b*, in which the ribbon is to be heated, and the bath *c*, through which the heated ribbon *e* is drawn by means of the reel or winding-drum *d*, may be of any 85 suitable or usual construction and arrangement.

The ribbon *e*, to be hardened, instead of being drawn progressively through the furnace or muffle, is coiled tightly, as shown at *e'*, Fig. 100 2, and inclosed in a heating-case, *f*, composed of iron or other metal not fusible at the tem-

perature to which the inclosed steel is to be heated. As herein shown, the said case consists of a main or body portion, *g*, having a flange, *h*, of a depth about equal to the width 5 of the ribbon to be hardened, provided with a central pin or stem, *i*, around which the coiled ribbon *c* is placed, and upon which the said coil revolves as a center when it is unwound. The said body is provided with a 10 trough-like nose, *k*, through which the ribbon passes when being unwound, it protecting the ribbon and keeping it heated until it enters the cooling-bath.

The case has a tight-fitting cover, *m*, shown 15 as fastened thereon by a nut, *n*, or equivalent, suitable fire-proof packing being applied before the cover is put on. The end of the ribbon is run out through the nose *k*, as shown, so that it may be readily taken hold of by 20 tongs to draw it out, and the end of the nose is plugged up tightly with asbestos or equivalent material, as shown at *p*, thus wholly preventing the access of air to the ribbon in the process of heating. The case is preferably 25 provided with a projection, *r*, to serve as a handle to enable it to be moved to the proper position in the muffle to draw out the ribbon, as shown in Fig. 1; or, if desired, the case may be wholly removed from the furnace before 30 the ribbon is drawn out from it, the case being of sufficient size to remain sufficiently heated until the ribbon is all drawn out from it. By thus protecting the ribbon from the air while it is being heated, its surface will be comparatively unchanged, so that it may be highly 35 finished or polished before being hardened, and will subsequently require but very little

treatment for making the finished springs, while by the usual process of progressively heating the ribbon it burns or oxidizes more 40 or less, so that it requires to have its surface subsequently polished at a large expenditure of labor, in order to give it the requisite finish. The spring-ribbon produced by my improved process is much tougher and less liable to be 45 broken in use than springs made by the processes heretofore employed.

I claim—

1. That improvement in the art or method of hardening steel ribbon for springs which 50 consists in coiling the ribbon and inclosing the coiled ribbon in a case or body of metal, heating it therein, and uncoiling or unwinding the heated ribbon and cooling the same as it is unwound, substantially as described.

2. The furnace, combined with a case inclosing the coiled ribbon to be hardened, and protecting the said ribbon from the air or gases in the furnace, and means to cool the said ribbon as it is unwound from the case, substantially as described.

3. The case having a flanged main or body portion and cover, combined with a central pivot for the coil of ribbon, the said case having a nose for guiding and protecting the ribbon as it is unwound from the interior of the case.

In testimony whereof I have signed my name to this specification in the presence of two subscribing witnesses.

JOHN LOGAN.
